UNITED STATES PATENT OFFICE

WILLIAM THAISON, OF AUSTIN, TEXAS.

BRICK-MACHINE.

SPECIFICATION forming part of Letters Patent No. 353,095, dated November 23, 1886.

Application filed January 7, 1886. Serial No. 187,849. (No model.)

To all whom it may concern:

Be it known that I, WILLIAM THAISON, of Austin, county of Travis, State of Texas, have invented a new and Improved Brick-Machine, 5 of which the following is a full, clear, and exact description.

The object of my invention is to provide a new and improved brick-machine which is simple in construction, compact, occupying 10 very little space, and produces a large number of bricks in a very short time.

The invention consists in the construction and combination of parts and details as herein-after described, and then specifically claimed.

Reference is to be had to the accompanying drawings, forming a part of this specification, in which similar letters of reference indicate corresponding parts in both the figures.

Figure 1 is a cross-sectional elevation of 20 my improved brick-machine. Fig. 2 is a sectional plan view of the same on the line *x x*, Fig. 1.

The frame of the machine is composed of the four uprights *A* and the connecting cross-braces *B*, united at the center by the neck *C*, in which revolves the heavy vertical shaft *D*, suitably stepped at its lower end. On the collar *E* on the shaft *D* the mold-wheel *F* rests, and is keyed to revolve with said shaft. Said 25 mold-wheel is provided with six, eight, or more radial mold-cavities, *G*, in its upper surface, which cavities are open at the top and bottom, and in each cavity is closely fitted a plunger, *H*, provided with two downwardly-projecting arms, *I*, between which a roller, *J*, is mounted to revolve on the shaft *K*, held in the lower ends of the arms *I*, and passed through the vertical guide-slots *L* in the lower parts or flanges, *M*, of the mold-wheel.

40 The plunger-arms *I* are held from sidewise movement by lateral guide pins or projections *N*, resting against the flanges *M* on either side.

The rollers *J* run on the cam-ring *O* on the base *P* of the machine, which cam-ring is of 45 varying height, so that the rollers running over it move up and down and impart said motion to the plungers *H* in the mold-cavities *G*.

Each mold-cavity has a steel lining, *G'*, and 50 the plunger therein a steel top; and at each cavity, at the inner side thereof, is hinged a

door, *Q*, fitting closely within said cavity, and having a transverse rib, *Q'*, on its upper surface, for a purpose hereinafter set forth.

The fixed hinge-lugs *R* of each door-hinge 55 have vertically-slotted eyes for the hinge-pin, so as to allow a slight vertical movement of the door out of the mold-cavity, and one swinging hinge-lug, *R'*, of each hinge is provided with a projecting shank, *R''*, forming an 60 angle-lever, said shank serving to prevent the door from swinging too far back when opened, and also as a lever to open the door when 65 acted upon by the cam projection *S* of the frame *B A*.

A segmental presser-arm, *T*, is pivoted in a downwardly-projecting lug, *U*, of the frame, and in one of the standards *A* of said frame, and extends over the top of the mold-wheel, the length of said arm being equal to about one-fourth of the circle. To the swinging end of 70 said arm the rod *V* is secured, which is passed through an aperture in the cross-piece *B*, and has a nut screwed on its outer end, thus allowing an upward movement of the arm *T*, but 75 checking its downward movement. On the swinging end of said arm *T*, beyond the rod *V*, is formed the head *W*, between which and the cross-piece *B* a powerful spiral spring, *a*, is held, which presses the arm *T* on the door-ribs *Q*, and can be adjusted to keep the doors closed against normal pressure from below, and yet yield and relieve the machine from 80 undue strain when an excess of clay has been placed in a cavity, *G*. Instead of the spiral 85 spring *a*, any other suitable form may be used, as desired. On the lug *U* of the frame a cam-rod, *b*, is secured, which strikes the doors *L* and swings them down to close the mold-cavities.

The clay is placed upon the hopper or platform *Z*, so that it can be shoveled into the mold-cavities, and the surplus clay is removed from each cavity to that succeeding by the scraper *e*, preferably of sheet metal, riveted to the under part of the scraper-frame *d*, formed 90 of two radial portions and an inner segmental part, the radial extensions being secured at their outer ends to the standards *A*. The scraper or knife *e* is slightly curved at its lower edge to cut more cleanly, and is provided with 95 a segmental wing, *e'*, secured to the corresponding part of the frame and extending 100

downward to the mold-wheel, to keep the surplus clay from clogging the doors. The cam-ring is lowest at the place where the cavities are filled, and highest a short distance beyond 5 the presser-arm T.

In operation the mold-wheel F is revolved by a motor of sufficient strength in the direction of the arrow a', Fig. 2. The clay is shoveled from the platform Z into the mold-cavities and upon the plungers G, at this time at their lowest position. After a mold-cavity has passed the scraper e the cam-rod b strikes the door of the same and swings it down in place, and then the doors pass under and are 15 kept in place by the presser-arm T. From the time each door is held in position by the presser-arm the corresponding plunger, H, is raised by its roller running up the incline of the cam-ring, and the clay, &c., in the mold- 20 cavity are gradually compressed, the pressure being greatest below the spring a, and the cam-ring being of the required height at that point to give the brick the proper size and shape. As the mold-cavities pass beyond the end of 25 the presser-arm the hinge shanks or levers R² strike the cam projection S, and the pressure being removed thereby swing open the doors, allowing the bricks, raised out of their cavities on account of the increased height of the cam- 30 ring, to be removed and carried away. The plungers then immediately descend, and when at their lowest point are at the hopper or platform S to receive a fresh charge, and so on. For each revolution as many bricks are made 35 as there are mold-cavities in the mold-wheel, these cavities and their plungers being of any shape, according to that of the brick desired. The height of the cam-ring at the place of filling is regulated so as to insure a proper charge 40 for the molds, to give the bricks when compressed the required size; but as clay is of varying composition the charge is not always exact, and hence I provide the spring-acted presser-arm to relieve the machine from 45 strains, as stated.

Having thus fully described my invention, I claim as new and desire to secure by Letters Patent—

1. In a brick-machine, the combination, with 50 a mold-wheel mounted to revolve in the horizontal plane and provided with mold-cavities, of a plunger in each cavity, lateral guide-pins on the lower end of the plunger and resting against the lower parts of the mold-wheel, a 55 shaft mounted on the lower end of each plunger and passed through vertical guide-grooves in the said lower parts of the mold-wheel, a roller on each shaft, and a cam-ring on which the rollers run, substantially as herein shown and 60 described.

2. In a brick-machine, the combination, with 65 a mold-wheel mounted to revolve in the horizontal plane and provided with mold-cavities, of a door for each cavity, hinged on the top of the mold-wheel, each door being provided with a central transverse rib and its hinge-lug with

a lever arm or shank, and of cams acting on the doors and their hinge-levers for raising the doors for swinging them down on the top of the wheel, substantially as herein shown 70 and described.

3. In a brick-machine, the combination, with a rotary mold-wheel provided with mold-cavities, of a movable plunger in each cavity, a door for each cavity hinged on the mold-wheel, 75 and a curved spring-acted presser-arm arranged to act upon the hinged doors, substantially as specified.

4. In a brick-machine, the combination, with a mold-wheel mounted to revolve in the horizontal plane and provided with mold-cavities, of a vertically-movable plunger in each cavity, a door for each cavity hinged on the top of the wheel, the hinge plate or lug attached to the mold-wheel being slotted to allow a vertical movement of the hinge-pin, a curved arm pivoted over the top of the mold-wheel and extending over part of the same, and a spring acting on the swinging end of said curved arm, substantially as herein shown and 90 described.

5. In a brick-machine, the combination, with a mold-wheel mounted to revolve in the horizontal plane and provided with a series of mold-cavities, of a plunger in each cavity, a door for each cavity hinged on the top of the wheel, so as to allow of a slight vertical movement, a curved arm pivoted above the mold-wheel and extending over part of the same, the rod V, connected with the swinging end of 100 said arm and passed through the top of the frame of the machine, and of a spiral spring resting on the head on the end of the curved arm, substantially as herein shown and 105 described.

6. In a brick-machine, the combination, with a frame and a mold-wheel mounted to revolve in the horizontal plane and provided with a series of mold-cavities, of a plunger in each cavity, a door for each cavity hinged on the top of the mold-wheel and adapted to move 110 vertically a short distance when swung down, an arm extending over part of the wheel, which arm is acted upon by a spring, and of a scraper secured to the frame of the machine and projecting over the cavities of the mold-wheel, 115 substantially as herein shown and described.

7. In a brick-machine, the combination, with the frame-uprights A and the horizontally-revolving mold-wheel F, having mold-cavities 120 G, of the scraper-frame d, having radial and segmental parts, and secured at its outer ends to the standards A, and of the scraper e, secured on the radial and segmental parts of said frame, substantially as herein shown and 125 described.

8. In a brick-machine, the combination, with a frame and a mold-wheel mounted to revolve in the horizontal plane and provided with a series of mold-cavities, of a vertically-movable plunger in each cavity, rollers on the 130 lower ends of the plungers, a cam-ring having

different heights, on which ring the plunger-rollers run, a presser-arm extending over part of the top of the wheel and acted upon by a spring, and of a hopper for receiving the clay 5 before it is delivered upon the mold-wheel, the height of the cam-ring being greatest a short distance beyond the presser, and lowest at the hopper, whereby the plungers are gradually moved upward toward the presser, and

then still farther upward beyond the presser to eject the bricks, and are then moved down toward the hopper, substantially as herein shown and described.
